US00D718464S

(12) **United States Design Patent**
Schroer et al.

(10) **Patent No.:** US D718,464 S
(45) **Date of Patent:** ** Nov. 25, 2014

(54) **MAGNETIC STIRRER**

(71) Applicant: **IKA-Werke GmbH & Co. KG**, Staufen (DE)

(72) Inventors: **Erhard Schroer**, Ulm (DE); **Sebastian Wiegert**, Freiburg (DE)

(73) Assignee: **IKA-Werke GmbH & Co. KG**, Staufen (DE)

(**) Term: **14 Years**

(21) Appl. No.: **29/480,836**

(22) Filed: **Jan. 30, 2014**

Related U.S. Application Data

(62) Division of application No. 29/420,236, filed on May 7, 2012, now Pat. No. Des. 701,616.

(57) **CLAIM**

The ornamental design for a magnetic stirrer, as shown and described.

DESCRIPTION

FIG. 1 is a top, front, right perspective view of a magnetic stirrer in accordance with my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

The broken lines shown form no part of the claimed design.

1 Claim, 6 Drawing Sheets
